Inventor:

UNITED STATES PATENT OFFICE.

HARFORD W. HARE POWEL, OF NEWPORT, RHODE ISLAND.

DEVICE FOR INKING DRAFTSMEN'S PENS.

SPECIFICATION forming part of Letters Patent No. 663,131, dated December 4, 1900.

Application filed April 27, 1899. Serial No. 714,659. (No model.)

To all whom it may concern:

Be it known that I, HARFORD W. HARE POWEL, a citizen of the United States of America, residing in the city and county of Newport, in the State of Rhode Island, have invented a certain new and useful Improvement in Devices for Inking Draftsmen's Pens, of which the following, reference being had to the component drawings, is a true and exact description.

My invention relates to devices for applying ink to draftsmen's pens.

So far as I am aware the practice has been when his drawing or "bow" pen needed ink for the draftsman to let go of his T and other squares, &c., and with his left hand to take an ordinary writing-pen, a slip of paper, or a quill or pipette attached to the lower side of his inkstand-cork and dipping it into the ink to secure thereon a drop and by contacting the same between the blades of his pen to charge the latter, the drawing-pen being held the while in the draftsman's right or pen hand, and then (not to mention wiping his pen, laying in a safe place said ink-carrier, &c.) to return to his probably dislocated squares and drawing. Now by my invention (hereinafter described) I provide draftsmen with a device whereby it becomes unnecessary to let go of T-squares, &c., or to use any but the pen-holding hand, and of it to use possibly only such portions as are not engaged in the ordinary grasp of the pen. By this means I reduce to a minimum the number of hands occupied in the act, as well as the number of motions, save time, make the ink-charges substantially uniform in amount, and afford with its incidents a cleanly, simple, and durable machine in place of crude ink-scattering haphazard hand-tools.

The new and useful features of my said invention will be found segregated in the concluding claims, and reference now being had to the above-mentioned drawings, they will be found to illustrate the same as follows:

Figure 1 is a partially-sectioned side elevation of a simple embodiment of my invention. Fig. 2 is a plan view of device shown in Fig. 1, the broken line 1 1 denoting plane of sections, Fig. 1. Fig. 3 is a partially-sectioned side elevation of a preferred modifica-

tion. Fig. 4 is a plan view of modification, Fig. 3, the broken line 3 3 denoting plane of sections, Fig. 3. Fig. 5 is a front elevation of a group of parts comprised in Figs. 3 and 4 in the act of assembling. Figs. 6 and 7 are respectively side elevation and transverse "thin" section on line 6 6 of Fig. 6 of a modification of a detail. Fig. 8 is a partially-sectioned elevation, similar to Fig. 3, of a further amplification of preferred modification. Fig. 9 is a similar view of a still further modification.

In Fig. 1, A is a block of preferably porcelain, slate, or other material of "tooth" suitable for grinding india-ink. Sunk in the top of this block is the usual annular inwardly-sloping ink-grinding surface *a* and contiguous central well *W*, into which well the said grinding-surface drains. To the margin of the block I connect, through countersunk hole *a'*, screw *s*, and nut *n*, having hinge-lugs *l l'* and pivot-pin *p*, a reciprocating arm *B*, a short lever extension of which arm, having a twist given its mid-body, forms at its end a fingering part or key *k*, while the other end *b*, which is not only longer, but of sufficient reach and proper blade-like character for the purpose, extends to and either dips into the ink (designated by parallel broken lines) in the well *W* or, if the blade be vibrated up by pressing upon key *k*, issues therefrom and banking in a substantially horizontal position on shoulder *l'* of the hinge-nut *n* exposes itself above the block charged with adhering ink. This position is indicated in Fig. 1 by broken-line outline *b'* and is a suitable one for the draftsman to straddle over the ink-carrying end *b* the blades of his pen, to contact with the liquid ink thereon the inside of one of said blades, and so to charge his pen. If the blades of the pen become clogged, pulling the straddled pen across the blade *b* acts to clean them out. In this act and in the blade-straddling and ink-charging acts the fact that the (preferably "little") finger of the draftsman's hand after tilting up the arm *B* still rests upon its fingering part the key *k* gives him a most desirable point of support and facilitates the speedy, cleanly, and accurate charging of his pen. If not drawn across the blade, and in most cases it is not, the charged

pen is readily removed by an opposite or unstraddling movement, which movement, like both the former, is well within the finger-flexing motions of the pen-holding hand 5 alone. As soon as the charged pen is clear of the ink-carrying blade b the draftsman takes his finger off of the key, and the preponderance of the well-reaching end tilts the arm and its end b reimmerses in the ink. 10 Left in this way between the charging acts prevents remnants of ink not charged from drying on and gumming up the blade. 15 As a naked well of ink is prone to become dusty, rapidly evaporate, and thicken, I prefer to combine with above simple form of my invention a cover, (indicated at C in Figs. 1 and 2.) This cover C , being detachable, slotted, and conforming in size and shape, fits in the "rabbet" or shoulder of the afore- 20 said countersunk grinding-surface. There steady-pins c' , fixed to and protruding from the under side of cover C , localize its slot C' in respect to the ink-carrying blade's path by engaging with registering holes a^2 a^2 , sunk 25 into the inkstand or block A . A shutter C^2 , having a fingering-lug c^2 , is also preferably pivoted at c^3 to cover C and when the blade b is up serves completely to cork the well W . When the blade is down, the shutter C^2 is 30 of course placed to one side; but then the sides of slot C (though sufficiently far apart to clear the ink-charges borne upon the blade end b) are yet so close that when said blade is down they afford little room for access of 35 dust, evaporating air-currents, &c.

While the blade b may be made of a variety of materials—such as steel, brass, hammered silver, celluloid, &c.—those least subject to corrosion or of themselves least wearing to the pen-blades if drawn across are 40 preferable.

The mode of operation having been incident to above description of the forms shown in Figs. 1 and 2, I now pass to the description of preferred modification. (Illustrated in 45 Figs. 3 and 4.) Here the well-reaching blade b^30 is curved or scimeter-shaped. When exposed, it has, instead of a horizontal, as form Fig. 1, a pendent position and is connected 50 not directly to well-block A^30 , but to a detachable cover C^30 , which cover by ground meeting faces sits tight upon the margin a^34 , surrounding said well-block's ink-rubbing surface a^30 . Rubber bands R bind cover 55 C^30 in position and also on the under side of block A^30 afford good non-slipping feet for steady repose. This cover, which I prefer to make of glass, celluloid, or similar transparent material, has over the well W^30 an aperture C^31 of such size and figure as amply to clear blade b^30 in its path to and from the ink-well W^30 , in which ink is indicated by parallel broken lines. This modified ink-carrying 60 blade end b^30 is made separate from, but removably connected with, a cranked upstanding rock-arm part B^30 , which arm part toward the

well and at its free end has an engaging device or "chuck" consisting of a cleft end forming lugs b^{32} b^{33} , between which said blade (after the manner of an ordinary pen and penholder) 70 may be inserted and removably held; but for the better doing thereof I prefer also to equip the device with a mortise extension b^{34} and a screw s^{30} , passing through one and thread- 75 ing into a tapped hole in the other, b^{32} , of said lugs, as well as through a suitable aperture in the butt of said blade, which blade is likewise provided with a tang b^{35} , registering with the mortise aforesaid. On inspecting Fig. 5 the blade-clenching lugs of this rock-arm part 80 B^30 will be seen to be oblique, for I prefer to slant the ink-carrying blade b^30 , which they hold, into that line which experience has shown me the pen with proper manipulation assumes in the ink-charging acts, and thus I 85 reduce what in the charging, nib-clearing, or unstraddling acts otherwise might require a wrist movement to a mere finger-joint flexing. This slant of the ink-carrying part of the blade is of special value if the little finger of the pen-hand finds, as it is designed to do during the whole act, a point of support on the key h^30 , which key in this preferred form is of a struck-up or concave saucer shape and attached, as by being integral 90 with, hard soldering, riveting, &c., to the upper and swinging part of arm B^30 . Any suitable abutment, as flat b^{36} on the hinge part of the arm B^30 , serves to limit the upward motion of the blade at a proper exposing position above cover C^30 , which position thus definable is not further illustrated. In it, however, the carrier-blade b^30 should stand exposed with its point pendent, and thus tend to have the carried ink collect by gravity on 95 its extremity. A flanged cap C^{32} , somewhat larger in area than the perforation C^{31} in cover C^30 , is preferably attached above the blade-chuck to the well-reaching parts and in such manner that it serves to closely cover said perforation whenever blade b^30 is in its ink-secur- 100 ing position, thus on and as an incident of the return of the blade I automatically and completely closing the well. The curved and pendent form of the blade b^30 causes it to apply, if not to carry, more ink for a similar area of blade than does a straight substantially horizontal blade like b aforesaid. An interchangeable corrugated blade b^{60} (shown 105 in Figs. 6 and 7) by reason of its quasi capillarity, increased surface, &c., carries still more ink and as indicated by the tang b^{65} and adjoining screw-hole, is adjustable to the chuck of arm B^30 . (Shown in Figs. 3 and 4.) As a still further step in this the graded ink-carrying capacity of my invention, which for 110 "detail" and long heavy-line drawing-pens is important, I have also shown in Figs. 8 and 9 a valveless pump, pipette, or dropper device, combined with well-connected parts 115 B^30 B^{90} , and provided them with well-reaching blades b^{80} and b^{90} , respectively, or in detail in 120

Fig. 8 I show, with well-block A⁸⁰, swinging slotted cover C⁸⁰ and pivotally (p⁸⁰) connected arm B⁸⁰, which has a hollow cylindrical head b⁸³ and an attached well-reaching tube T. The rear end of this tube is open and upturned and has, in the manner of pipettes, slipped over it the grasping-neck u of a hollow elastic bulb U. Upon the other end of the tube T a cranked tubular part t', of reduced or tapering section-ends, preferably, in a diagonally-cut and flattened capillary blade b⁸⁰. Upon the mid outer body of tube T a hollow conical cork C⁸² is fixed, so as when the pipette is swung down for ink to project into and close the cover-aperture C⁸¹ or as is shown in Fig. 8. In this position the bulb U can be collapsed between the small disengaged fingers and palm of the pen-holding hand, air expelled, the bulb released, ink drawn in, and by a touch of some of said members the pipette tilted up. Then blade b⁸⁰ being clear of cover C⁸⁰, a second squeeze by same members will, the pen-blades being straddled over the ink-carrying blade, cause the ink in quantity to be ejected and lodged between said pen-blades. The bulb-carrying end of the pipette-tube is turned up in order to prevent ink when drawn into the tube's cavity from running back into the bulb, and thus causing air-bubbles or even inaction of the device. A subsidiary shutter C^{82*} may also, as shown in Fig. 8, be pivoted to cover C⁸⁰ and by being swung over the cover-slot C⁸¹ when the pipette is up exclude air, &c.

In Fig. 9 instead of a vibratory reciprocation the movement to and from the well W⁹⁰ is rectilinear and made by a smooth straight tubular dropper B⁹⁰, whose mid-body is engaged in the suitably light frictional grasp of the coiled head b⁹⁸ of a stanchion B⁹⁸, the flanged and screw-pivoted foot b⁹⁶ of which screwing into a registering tapped hole c⁹⁵ in cover C⁹⁰ attaches the same with the axis of said spirally coiled and slanting head pointed at the well-aperture C⁹¹, along which line can be readily slid the dropper B⁹⁰, grasped between the small fingers and palm of the pen-holding hand. Below and parallel with an extension of this line of movement and at proper intervals, as illustrated in Fig. 9, two abutments I I', fixed to the said cover in the manner of the stanchion aforesaid, afford limits of motion and banks upon which the collapsible bulb U⁹⁰ of said dropper may be actuated, on the one nearest said stanchion for the filling and on the other for the ejection of ink from the blade, which blade is here the capillary tube end b⁹⁰ of said dropper and acts in a manner which should be so patent from the foregoing of a pipette's action in form Fig. 8 as not to require further description.

In the form illustrated in Fig. 9 the cover C⁹⁰ is flanged and laterally fixed to the well by 65 a rabbeted seat c⁹¹, and the ink-rubbing sur-

face a⁹⁰, a unilateral slope, all of which is familiar and only touched on to show that I do not wholly limit myself to a particular form of well or inkstand; but the cover-slot C⁹¹, which in plan presumably comes close to or 70 conforms with the section of the tubular-parts that pass into it, is, in combination with said parts, &c., a further illustration of a modified self-closing pen-inking machine of my present invention. Also as the ink-securing 75 duct d⁹⁰ of the blade b⁹⁰ is fine the amount of air, dust, &c., which after loading can there- by enter the cavity of the dropper B⁹⁰ is so small as in practice to be negligible, which fact, coupled with the fact that the capacity of the 80 pipette or dropper may in this case be made nearly or quite equal to that of the well, shows a still further aspect in the scope and protean character of the broad claims of my invention.

The droppers and their blades, Figs. 8 and 9, may be of glass or metal, &c. The fragile character of the former, especially in case of the form Fig. 8, however, is not preferred. In fact, while the material of the blades in 90 the forms shown in the drawings may be various, I prefer to make them of pen-steel, brass, or hammered silver.

In Figs. 1 and 2 I have shown immediate mechanical connection between the ink-well 95 and the ink-carrying blade—viz., pivot p. In the modifications Figs. 3, 4, and 8, respectively, the connection of the aforesaid elements of combinations is mediate or by vibrating arms pivoted to a cover. Moreover, 100 these arms B³⁰ B⁸⁰, respectively, act as tumblers, for by reason of their centers of gravity crossing the vertical plane between their ink-immersing (or down) and up (or "exposing") 105 positions they naturally "stay put" either up or down, whereas the immediately-connected blade end b of the form shown in Fig. 1, having a preponderance over its shorter key end unless prevented by shutter C², automatically seeks and keeps the well. In the form Fig. 110 9 rectilinear takes the place of vibratory reciprocation, and the mechanical connection (whereby the ink-carrying blade b⁹⁰ is to be placed alternately within said well or "exposed") is the above-described combined au- 115 tomatic clutch and coiled guiding-head h of the dropper-supporting stanchion H, which well and blade connection, contrasted with the pivoted ones of the first forms, further illustrate the scope of certain following claims. 120

In Fig. 8 the rock-arm B⁸⁰ works in and be- 125 tween depressed lugs, of which only one, l⁸¹, is shown, p⁸⁰ denoting the pivot. In Figs. 3, 4, and 5 in place of such immediate hinging preferably metallic lugs l³⁰ l⁸⁰ form a chair 130 which by rivet r is fixed to a suitable perforation (see Fig. 3) in cover C³⁰, and for glass or celluloid or other friable sorts of cover is preferred to integral cover-lugs, like l⁸¹.

Having fully described my invention, what I claim, and desire to secure by Letters Patent of the United States, is—

1. The combination of an ink-well, a blade, 5 a support for presenting said blade in an exposing position, and means for operating said blade substantially as described.
2. The combination with an ink-well of an 10 ink-carrying blade, and mechanical connections with the well whereby said blade can be placed alternately in an ink-immersed and in an exposing pen-charging position, substantially as described.
3. The combination of an ink-well, a movable 15 ink-carrying blade, and mechanical connections whereby said blade may be actuated by one hand, substantially as described.
4. The combination of an ink-well and a 20 pivotally-connected ink-carrying blade, substantially as described.
5. The combination of an ink-well, an ink-carrying blade, a pivotal connection, and a finger-key, substantially as described.
6. The combination with an ink-well of a 25 movable arm provided with a "chuck" or blade-engaging parts, and a removable blade adapted to be chucked or engaged therewith, substantially as described.
7. The combination of an ink-well, a perforated 30 cover, a connected ink-carrying blade adapted to move through the perforation of
8. The combination of an ink-well, a mov- 35 ably-attached ink-carrying blade, and a cov- ering part operative to close said well when said blade is therein projected, substantially as described.
9. The combination of an ink-well, an ink- 40 well cover provided with an aperture com- municating with said well, an ink-carrying blade operatively connected therewith, and, attached to said blade, a subsidiary cover adapted, when the blade is immersed, to close 45 said aperture substantially as described.
10. The combination of an ink-well an ink- carrying blade, and mechanical connections whereby said blade, alternately may be im- 50mersed in said well and moved to and from a pendent exposed position, substantially as described.
11. The combination with a friable ink- stand-cover, having an aperture, of an at- 55 tached hinge-arm of non-friable material, and an ink-carrying blade thereby opera- tively connected, substantially as described.
